(57) **CLAIM**

The ornamental design for an electric heater cover for nerve stimulator device, as shown and described.

DESCRIPTION

FIG. 1 is a front view of an electric heater cover for nerve stimulator device showing our new design;

FIG. 2 is a rear view thereof;

FIG. 3 is a left side view thereof;

FIG. 4 is a right side view thereof; and,

FIG. 5 is a top view thereof, the bottom view being a mirror image.

The broken lines depict portions of the electric heater cover for nerve stimulator device which form no part of the claimed design.
